[57] CLAIM

I claim the ornamental design for an electrical cord clamp,
as shown and described.

DESCRIPTION

FIG. 1 is a perspective view of an electrical cord clamp
showing my new design;

FIG. 2 is a front elevational view thereof;

FIG. 3 is a rear elevational view thereof;

FIG. 4 is a left side elevational view thereof, the right side
elevational view being a mirror image of this Figure;

FIG. 5 is a top plan view thereof; and,

FIG. 6 is a bottom plan view thereof.

The broken line illustration in FIG. 1 represents an electrical
receptacle cover plate as is not part of the design to be
patented.
